UNITED STATES PATENT OFFICE.

HOSEA K. KRIEBEL, OF WEST POINT, PENNSYLVANIA.

REGULATOR FOR STEAM-HEATERS.

SPECIFICATION forming part of Letters Patent No. 363,470, dated May 24, 1887.

Application filed July 19, 1886. Serial No. 208,405. (No model.)

To all whom it may concern:

Be it known that I, HOSEA K. KRIEBEL, of West Point, county of Montgomery, and State of Pennsylvania, have invented an Improvement 5 in Regulators for Steam-Heaters, of which the following is a specification.

My invention has reference to regulators for controlling the draft of steam or hot-water heaters for buildings; and it consists in certain 10 improvements, all of which are fully set forth in the following specification, and shown in the accompanying drawing, which forms part thereof.

Automatic regulators have been used to control the draft-door and chimney-damper to regulate the temperature of the fire and pressure of the steam, and this device has been worked by a suitable lever mechanism controlled by a diaphragm actuated either by the 20 steam or hot water in the boiler.

The object of my invention is to provide suitable means, in case of the rupture or destruction of the regulator-diaphragm, to automatically and positively close the draft-door 25 and chimney-damper or smother the fire, and thereby prevent danger, which would otherwise arise from an excessive generation of steam.

In carrying out this invention I connect the 30 draft-door and damper to the regulating-lever by means of unlatching devices, which normally are locking, so that the said draft-door and damper are operated by the movements of the regulating-lever; but in case of the rupture 35 of the diaphragm-regulator these latches are tripped and the draft-door and damper will instantly close.

In the drawing is shown a sectional elevation through the regulating apparatus, and 40 showing its connection with the draft-door and damper.

A represents the body of the heater.

B is the regulator proper, and is formed into an upper compartment, b, and the lower compartment, b', supported by a lever or flexible diaphragm, C. The lower compartment, b', connects with the heater above or below the water-line by a pipe, a, it being equally adapted to hot water or steam.

50 The diaphragm C in its movements reciprocates the rod D, which is connected to the regu-

lating-lever E, and whereby the latter is oscillated. The lever E is pivoted at e close to the rod D. The rod D passes through an opening, d, in the top of the compartment b, and is provided with a valve-packing ring, F, which, when the rod D is fully depressed, closes the opening d and forms a valve, the object of which is to prevent the escape of steam or water in case of the rupture of the diaphragm C. The lever E is weighted at E', so as to tend to depress the diaphragm.

G is the draft-door, and connects by a link, g, with the latch I, and pivoted to the lever E at i, and having the hook-support I', over 65 which the link catches. This latch is held in operative position by a lock, J, which is operated by a flexible diaphragm, k, formed as a head to the pressure-chamber K. This pressure-chamber K connects by a flexible pipe, L, 70 with the upper compartment, b, of the regulator and is carried by the lever E, to which it is secured, as shown, in order that the relative positions of the pressure-chamber and lever may be maintained in all positions of the 75 lever. The chimney-damper H is connected by a link, h, having an eye, Q, at the bottom, through which the bolt N passes to attach it to the other end of the lever E. This bolt N is carried by a frame, O, made adjustable on 80 the end of the lever E by set-screw P. This bolt is connected by a cord or wire with the latch I, so that when the said latch is tripped the bolt is withdrawn.

The operation is as follows: The apparatus 85 being connected as shown and under normal operation, any variations in the temperature of the water or pressure by the steam will affect the diaphragm C and, through the mediation of the rod D, oscillate the lever E to open 90 or close the draft-door G and damper H to automatically suit the requirements and prevent an excessive steam-pressure. If in time the diaphragm C becomes worn out or weakened and is ruptured, the steam or water will pass 95 from the compartment b' into the compartment b, and as the valve F is closed, due to the action of the weighted lever, the water or steam enters pipe L and acts upon the diaphragm k. This actuates the lock J, causing 100 it to free the latch I, whereupon the weight of the door G oscillates the said latch to free the

link *g*, and said oscillation of the latch withdraws the bolt *N*, simultaneously releasing the chimney-damper and causing it to close with the closing of the draft-door. The heater is then closed up and the fire becomes reduced in temperature, or is smothered out altogether.

It is evident that in place of the valve *F* being formed by a ring of packing material, as shown, any ordinary metal-seated valve may be used, and in place of the diaphragm *k* to operate the lock and piston a cylinder-connection may be used, as indicated in dotted lines. It is also evident that in place of the bolt *N* a latch similar to that shown at *I* might be used for the chimney-damper, and said damper-latch might be operated directly from the lock *J*, as indicated in dotted lines, instead of being operated from the latch *I*. I therefore do not limit myself to the details of construction shown, it being possible to modify them in a large number of ways without departing from the spirit of the invention.

Having now described my invention, what I claim as new, and desire to secure by Letters 25 Patent, is—

1. In a regulating apparatus for a steam or hot-water heater, the combination of an oscillating lever, a diaphragm connecting with said lever and actuated by the steam or water of the heater, a draft-door, and a latch to connect and disconnect said door with said lever, substantially as and for the purpose specified.

2. In a regulating apparatus for a steam or hot-water heater, the combination of an oscillating lever, a diaphragm connecting with said lever and actuated by the steam or water of the heater, a chimney-damper, and a latch to connect and disconnect said damper with said lever, substantially as and for the purpose specified.

3. In a regulating apparatus for a steam or hot-water heater, the combination of an oscillating lever, a diaphragm connecting with said lever and actuated by the steam or water of the heater, a draft-door, a chimney-damper, and latches to connect and disconnect said door and damper with the lever, substantially as and for the purpose specified.

4. In a regulating apparatus for a steam or hot-water heater, the combination of an oscillating lever, a diaphragm connecting with said lever and actuated by the steam or water of the heater, a draft-door, a chimney-damper, latches to connect and disconnect said door and damper with the lever, and a connection between said latches whereby both latches are operated simultaneously, substantially as and for the purpose specified.

5. In a regulating apparatus for a steam or hot-water heater, the combination of a vessel, a flexible diaphragm dividing said vessel into two compartments, a pipe connecting one compartment with the heater to supply steam or water, a pivoted lever oscillated by the movements of the diaphragm, a draft-door, a latch to detachably connect said door to the lever, a pressure-chamber, a movable diaphragm or

surface, a lock actuated by said movable diaphragm or surface to actuate said latch, and a pipe or passage-way opening from the pressure-chamber and connecting with the other compartment of the vessel, whereby, if the diaphragm of the vessel breaks, the door is automatically closed, substantially as and for the purpose specified.

6. In a regulating apparatus for a steam or hot-water heater, the combination of a vessel, a flexible diaphragm dividing said vessel into two compartments, a pipe connecting one compartment with the heater to supply steam or water, a pivoted lever oscillated by the movements of the diaphragm, a chimney-damper, a latch to detachably connect said damper to the lever, a pressure-chamber, a movable diaphragm or surface, a lock actuated by said movable diaphragm or surface to actuate said latch, and a pipe or passage-way opening from the pressure-chamber and connecting with the other compartment of the vessel, whereby, if the diaphragm of the vessel breaks, the damper is automatically closed, substantially as and for the purpose specified.

7. In a regulating apparatus for a steam or hot water heater, the combination of a vessel, a flexible diaphragm dividing said vessel into two compartments, a pipe connecting one compartment with the heater to supply steam or water, a pivoted lever oscillated by the movements of the diaphragm, a chimney-damper, a latch to detachably connect said damper and door to the lever, a pressure-chamber, a movable diaphragm or surface, a lock actuated by said movable diaphragm or surface to actuate said latch, and a pipe or passage-way opening from the pressure-chamber and connecting with the other compartment of the vessel, whereby, if the diaphragm of the vessel breaks, the damper and door are both automatically closed, substantially as and for the purpose specified.

8. In a regulating apparatus for a steam or hot-water heater, the combination of a vessel, a flexible diaphragm dividing said vessel into two compartments, a pipe connecting one compartment with the heater to supply steam or water, a pivoted lever oscillated by the movements of the diaphragm, a connecting-rod extending up through the roof of the vessel and connecting the lever and diaphragm, a valve or seal to make the entrance of said rod steam or water tight when fully lowered, a draft-door, a latch to detachably connect said door to the lever, a pressure-chamber, a movable diaphragm or surface, a lock actuated by said movable diaphragm or surface to actuate said latch, and a pipe or passage-way opening from the pressure-chamber and connecting with the other compartment of the vessel, whereby, if the diaphragm of the vessel breaks, the door is automatically closed, substantially as and for the purpose specified.

9. In a regulating apparatus for a steam or hot-water heater, the combination of a vessel, a flexible diaphragm dividing said vessel into

two compartments, a pipe connecting one compartment with the heater to supply steam or water, a pivoted lever oscillated by the movements of the diaphragm, a connecting-rod extending up through the roof of the vessel and connecting the lever and diaphragm, a valve or seal to make the entrance of said rod steam or water tight when fully lowered, a chimney-damper, a latch to detachably connect said damper to the lever, a pressure-chamber, a movable diaphragm or surface, a lock actuated by said movable diaphragm or surface to actuate said latch, and a pipe or passage-way opening from the pressure-chamber and connecting with the other compartment of the vessel, whereby, if the diaphragm breaks, the damper is automatically closed, substantially as and for the purpose specified.

10. The combination of the vessel B, having diaphragm C, forming compartments b b', pipe a, connecting the compartment b' with the boiler, pivoted lever E, connecting-rod D, actuated by the diaphragm C, connecting with lever E and working through opening d in the vessel B, a valve, F, to close said opening d when the rod D is fully lowered, and suitable draft-controlling dampers operated by said lever E, substantially as and for the purpose specified.

15. 11. The combination of the vessel B, having diaphragm C, forming compartments b b', pipe a, connecting the compartment b' with the boiler, pivoted lever E, connecting-rod D, actuated by the diaphragm C, connecting with lever E and working through opening d in the vessel B, a valve, F, to close said opening d when the rod D is fully lowered, draft-door G, link g, a latch connecting said lever E with said link, a receptacle, K, a pipe, L, connecting said receptacle with the compartment b, a movable diaphragm for said receptacle, and a

lock actuated by said diaphragm to free the latch, substantially as and for the purpose specified.

12. The combination of the vessel B, having diaphragm C, forming compartments b b', pipe a, connecting the compartment b' with the boiler, pivoted lever E, connecting-rod D, actuated by the diaphragm C, connecting with lever E and working through opening d in the vessel B, a valve, F, to close said opening d when the rod D is fully lowered, damper H, a link, h, connecting it with the lever, a latch connecting said lever E with said link, a receptacle, K, a pipe, L, connecting said receptacle with the compartment b, a movable diaphragm for said receptacle, and a lock actuated by said diaphragm to free the latch, substantially as and for the purpose specified.

13. The combination of the vessel B, having diaphragm C, forming compartments b b', pipe a, connecting the compartment b' with the boiler, pivoted lever E, connecting-rod D, actuated by the diaphragm C, connecting with lever E and working through opening d in the vessel B, a valve, F, to close said opening d when the rod D is fully lowered, draft-door G, link g, a latch connecting said lever E with said link, a receptacle, K, a pipe, L, connecting said receptacle with the compartment b, a movable diaphragm for said receptacle, a lock actuated by said diaphragm to free the latch, a chimney-damper, H, link h, bolt N, to hold said link to lever E, and a cord or wire connecting the latch I and bolt, substantially as and for the purpose specified.

In testimony of which invention I hereunto set my hand.
